UNITED STATES PATENT OFFICE.

EDWIN W. GOODWIN, OF SOUTH BERWICK, MAINE, ASSIGNOR TO DEXTER FOLDER COMPANY, OF NEW YORK, N. Y., A CORPORATION OF NEW YORK.

VARIABLE SHEET-REGISTERING MECHANISM.

Application filed April 13, 1922. Serial No. 552,378.

This invention relates to sheet handling machines for automatically locating successive sheets of different sizes in suitable position in the machine to have operations performed thereon in corresponding arrangement determined by the sizes of successive sheets. The present invention is adaptable to machines for handling sheets of paper or fabric.

As shown on the drawings, this principle of operation is adapted to a sheet folding machine embodying sheet folding means operated at uniformly recurring intervals in connection with means for locating successive sheets of different sizes in position to present proportional parts of said sheets on opposite sides of the folding line imparted by said sheet folding means.

One of the objects of the present invention is to provide suitable means for locating successive sheets of different sizes under the control of suitable means for detecting the sizes of the successive sheets.

Other and further objects will appear in the specification and be pointed out in the appended claims.

The drawings show a preferred embodiment of my invention.

In the drawings:—

Figure 1 is a top plan view of a machine for folding textile fabrics of different sizes which may be fed to the folding mechanism in any order in which they happen to come to hand;

Figure 2 is a vertical longitudinal section of the same, parts being broken away and parts shown in section;

Figure 3 is a front elevation of the same;

Figure 4 is a front elevation on an enlarged scale on one end of one of the sheet gripping mechanisms taken on its lower run of the endless conveyer, parts being broken away and parts shown in section;

Figure 5 is a bottom plan view on an enlarged scale on the same end of said sheet gripping mechanism, parts being broken away and parts shown in section;

Figure 6 is a section on the line VI—VI

Figure 4, parts being shown in elevation;

Figure 7 is a section on the line VII—VII

device at the moment of release, surrounding parts being broken away and parts shown in section; and

Figure 24 is a front elevation of the same, 5 contiguous parts being shown in section.

In U. S. Patent No. 1,547,348 for folding machines, which was granted to Earl D. Rader under date of July 28, 1925, he has shown, described and claimed a folding machine 10 in which the sheets are drawn by suitable grippers travelling a predetermined path, said grippers being provided with suitable means for releasing a sheet when it has been brought into suitable position to be 15 folded by a folding blade. This machine was designed to accommodate only sheets of uniform size during any particular run of the machine. According to the present embodiment of my invention, the folding machine 20 is adapted to operate upon successive sheets of different sizes for folding said sheets in a uniform manner without manual adjustment. For this purpose, suitable means are provided under the control of each 25 of the sheets in succession for releasing said sheet from the grippers as soon as it reaches a predetermined position with respect to the folding mechanism and for varying the location of the folding line with respect to the 30 sizes of the sheet portions arranged on opposite sides of the folding line. For this latter purpose, in the embodiment shown and described, I employ variable driving connections between the gripper operating cam 35 and a sheet detecting finger which locates the edge of a sheet when said sheet has reached a predetermined position with respect to the folding line.

As shown in Figures 1 and 2, a feed table 40 1 which extends transversely of the machine and rests upon the side frames 2, is provided with a feed-off plate 3 which as shown in Figure 1 is provided with a series of notches 4 to accommodate a series of grippers as they 45 move into position to grip the forward edge of a sheet supported by the feed-off plate 3. As indicated in Figure 1, a motor 5 is provided with an armature shaft 6 carrying a small pulley 7, which is connected up by an 50 endless belt 8 to a large pulley 9 which is keyed to a transverse shaft 10. As shown in Figure 2, the transverse shaft 10 carries sprockets 11 which are keyed thereto and drive sprocket chains 12 which in turn drive 55 sprockets 13 keyed to a shaft 14 which is journaled in the side frames 2 on an axis parallel to that of shaft 10. A spur gear 15 which is also keyed to the shaft 14 meshes with an idler 16 which serves to transmit 60 power to a spur gear 17 keyed to a transverse shaft 18 disposed above shaft 14. Keyed to the power drive shaft 18 are laterally spaced sprockets 19 which serve to drive sprocket chains 20 which in turn drive the laterally 65 spaced sprockets 21 keyed to a transverse

shaft 22 which rotates upon an axis which is adjustable with respect to the axis of shaft 18. For this purpose, as shown in Figures 1 and 2, the shaft 22 has its opposite ends journalled in bearing boxes formed in slides 70 23 which are slidably mounted in suitable guides 24 on the opposite side frames of the machine. The adjustable movement of each of these slides is further constrained by means of a stud 25 which passes thru a slot 75 26 extending longitudinally of an extension 27 formed on the slide 23. Each of said slides is also provided with a forwardly projecting boss 28 which is threaded to receive the end of a stud 29 which is freely journaled in a lug 30 mounted on the side frame.

Gripper mechanism.

As shown in top plan in Figure 1 and in front elevation in Figure 3, each of the side frames 2 is provided with a double series of inwardly presented pads or bosses 32. Mounted in these bosses are stud bolts 31 which have their inner ends threaded into guide rails or tracks 33 which are thus spaced from the frames 2 (see Figure 9). Each of said guide rails 33 is therefore supported by a horizontal series of these studs 31, the upper and lower guide rails forming between them a longitudinal groove or slot. Within these grooves on opposite sides of the machine run gripper carriage cross-heads 38 (see Figure 5). The pins 35 together with the rollers 34 constitute elements in laterally spaced sprocket chains 20 which drive the gripper carriages, said rollers 34 being arranged between spaced side links 36 of the chains which are guided by 105 engagement with the rails or tracks 33. As shown in Figures 1 and 5, there are two pins 35 which constitute pintles in the sprocket chain 20 on either side of the machine. As shown in Figure 5, one of the pins 35 is socketed on a fixed axis in one 110 arm 37 of a cross-head 38, the other arm 39 of said cross-head being slotted to a depth indicated by the dotted line 40 in Figure 5 to provide a slot or guide way 41 within which is slidably adjustable the right angular end 42 of the other pin 35. By means of this device on either end of the transverse carriage, said carriage is 115 adapted to pass around the sprockets at the front and rear of the machine. At the right end of the carriage according to Figure 1 and oppositely disposed with respect to the cross-head 38 is a second cross-head 43. Said cross-heads 38 and 43 are rigidly connected by means of an angle iron 44 secured at opposite ends to the cross-heads 38 and 43 by means of bolts 45. Intermediately of the cross-heads 38 and 43, a plurality of gripper blocks 46 are secured to one leg 125 of the angle iron by means of stud bolts 47.

It will appear from an inspection of Figure 1 that the cross-heads 38 and 43 are provided with bearings 48 and 49 within which are oscillatably mounted the opposite ends 5 of a square gripper shaft 50. The left end of this shaft according to Figure 1 has keyed thereto a bevel pinion 51. Referring now to Figures 4 and 5, the bevel pinion 51 meshes with a bevel segment 52. A spur gear 53 10 which is oscillatably mounted on a stud bolt 54 is provided with a bushing extension 55 upon which the hub portions 56 of the bevel segment 52 is mounted. A bolt 57 extends thru the pivotal segment 52 and is threaded 15 into the spur gear segment 53 for rigidly connecting these elements. Meshing with the spur gear segment 53 is a reciprocable rod 58 which is provided with suitable rack teeth 59 for this purpose. As shown in 20 Figures 4, 5, 8 and 9, a grub screw 60 is threaded into the reciprocable rod 58 and is adapted to abut against a contiguous portion of the cross-head 38 for limiting the displacement of said rack in one direction. 25 As shown best in Figures 8, said rod or rack 58 is slidably mounted in suitable bearings 61 and 62, the right end of said rod according to Figure 8 being provided with a cylindrical socket or chamber 63. Rigidly mounted within three of the gripper blocks 30 35 40 45 50 55 60 65 70 75 80 85 90 95 100 105 110 115 120 125 130 135 140 145 150 155 160 165 170 175 180 185 190 195 200 205 210 215 220 225 230 D. Rader. Keyed to the rock shaft 244, are laterally spaced arms 245 which carry at their outer ends, a curved folder blade 246. As shown in the lower right hand portion of Figure 2, the laterally spaced endless chains 12, 12, carry a gripper mechanism which need not be described in detail since it is substantially similar to that already described above and corresponding parts 5 therein have been indicated by the same reference characters. As this gripper mechanism begins its upward movement around the right hand sprockets 13, its gripper fingers 71 are thrown into extreme open position by means of a cam track 247. Said cam track extends upwardly around the sprockets 13 and forwardly above the upper run of the endless chains 12 and terminates adjacent to the folder blade 246 in its 10 lowermost position. It will be understood from this description that the cam roller 70 (hidden behind the gripper blocks 46 according to the lower right hand portion of (Figure 2) is displaced by its engagement with cam track 247 and holds the movable gripper jaws open until the gripper mechanism reaches a suitable position to receive the folded edge of a sheet from the folder blade 246 in depressed position. As the 15 gripper mechanism reaches this position, the cam roller 70 leaves the cam track 247 and permits the grippers to close on the folded edge of the sheet for conveying it away preparatory to any further operation it may 20 be desired to perform upon it. For the sake of convenience in description, the mechanism for receiving the folded sheet from the folder blade and conveying it away from sheet-folding position may be termed the 25 receiving conveyer.

Gripper controlling mechanism.

In order to provide suitable means for opening the grippers at the predetermined 30 point in their travel for releasing a sheet to be operated upon by the folder blade, a cam block 80 (see Figures 9 and 10) is rigidly united to a block 81 which is secured by bolts 82 to a reciprocal bar 83 provided 35 with rack teeth 84. The cam block 80 when not positively locked, in the manner to be hereinafter pointed out, is adapted to slide along the lower guide rail or track bar 83 until it reaches a variable position depending 40 upon the size of the sheet in which position it is positively locked and thus adapted to throw the cam roller 70 and to operate the grippers to release the sheet. For this purpose, the spring 66 is made sufficiently 45 stiff to resist the drag of rack 84 and the parts driven thereby, and only yields to ride over the cam 80 when said cam becomes positively locked. When this occurs the grippers are opened to release the sheet in 50 position to be folded. As shown in Figure 55

12, the forward end of rack bar 83 intermeshes with a spur gear 85 which is keyed to a transverse shaft 86. The shaft 86 is journaled at one end in the left hand side frame 2 according to Figure 1, the right end of 60 said shaft being journaled in a bracket 87. As shown in Figure 18, the bracket 87 is supported by a transverse bar 88, supported at opposite ends by the side frames 2. As 65 shown in Figure 14, the bracket 87 is mounted on a common base 93 with a second bracket 94, provided with a bearing boss 95 within which the shaft 86 is journaled. Freely journaled on the shaft 86 is a spur gear 96 which meshes with a rack bar 107 70 for operating the variable control mechanism so as to determine the positions of the shafts with respect to the folding blade for successive sheets of different sizes. A spur gear 97 is connected by a spline or feather 98 75 to adapt it to partake of the rotary movement of the shaft 86 while at the same time adapting it to be thrown into and out of clutching engagement with the spur gear 96, the gear 97 for this purpose being provided 80 with a laterally projecting spur 98' which is adapted to engage in a suitable hole or socket 99 in the hub portion of the gear 96. Suitable means for moving the gear 97 into 85 and out of clutching engagement with the gear 96 are provided as follows. A rod 100 carries on its outer end a hand grip 101, whereby it may be slidably adjusted within the bracket 87. Said rod is provided with a lug 102 which projects into a circumferential groove 103 to adapt the rod 100 to impart an axial adjustment to the gear 97. An offset extension 104 is provided on its inner 90 end with a lug 105 which is so disposed with reference to a notch 106 formed in the lower edge of reciprocable bar 107 that the rod 100 is permitted to shift the gear 97 into and 95 out of engagement with gear 96 only when the rack bar 107 is in position to locate the notch 106 in the path of movement of lug 105. When the rack bar 107 is in this position, the entire gripper controlling mechanism is in a position which is hereinafter referred to as the initial position of the mechanism.

As shown in Figure 13, the gear 97 has been moved out of engagement with the gear 96 and is in mesh with a gear 108 which is keyed to a transverse shaft 109, this shaft being journaled in the brackets 87 and 94. Another gear 110 which is keyed to the shaft 109, is permanently in mesh with the broad face gear 96 which is loosely journaled upon shaft 86. For this purpose, the gear 96 is provided with a sleeve or expanded hub portion 111 which turns freely in the bearing bracket 94 and is provided with a collar 112 which holds it against axial displacement. It is to be noted in connection with the present embodiment of my invention, that the 110

gear 97 has twice the number of teeth as the gear 108, while the gears 96 and 110 are provided with the same number of teeth. On the right end of shaft 109 is keyed a pinion 113 as shown best in Figure 3, said pinion being in mesh with a reciprocable rack 114. As shown in Figures 23 and 24, the rack 114 has its inner end secured to a plate 115, said plate being secured to the rack 114 by means of bolts 116. Integral with the plate 115 is a bearing lug 117 which carries a stud or pivot 118 upon which is oscillatably mounted a latch 119 provided with a hook shaped end 120. The latch 119 is adapted to yieldably embrace a roller 121 journalled upon a pin 122 which depends from the gripper cross-head 123. Said gripper cross-head is arranged at the opposite end of the gripper mechanism with respect to the gripper cross-head 38. A normal tendency to hold the latch 119 in clutching engagement with the roller 121 is imparted by the compression spring 124 which is interposed between the plate 115 and an arm 125 carried by the latch 119. A latch-release arm 126 carries a depending pin 127 suitably arranged to be engaged by one of the spaced folding bars 128 whenever the sheet moving grippers reach a predetermined position with respect thereto.

Sheet releasing mechanism.

By referring to Figures 19, 20 and 21, it will be seen that the reciprocable rack 107 has its rear end connected to a travelling frame 129 which is adapted to reciprocate longitudinally of a latch bar 130, said latch bar being rigidly suspended from a cross-bar 131, by means of a depending arm 132. The cross-bar 131 is rigidly connected to the side frames of the machine. It will be seen that the frame 129 carries a transverse pivot 133 upon which is mounted an oscillatory sheet detecting finger 134. Connected to said finger 134, is a leaf spring 135, its forward end bearing against an adjustable abutment 136 so that in order to depress the finger 134, as shown in Figures 19 and 20, said spring must be flexed in a way that places it under stress and hence prepares it to throw the detecting finger as soon as it is released. As shown in Figure 22, suitable means for stiffening the sheet S for holding the finger 134, in depressed position, may be provided in the form of laterally spaced rods or supports 137, sufficient space being provided therebetween to permit said finger to swing upwardly when released. A second pivot 138 which is mounted in the frame 129, serves to pivot a dog 139 which is provided with a detent 142 and is acted upon by a compression spring 140, said detent being adapted to be engaged by a shoulder 143 on the finger 134, for holding the dog 139 away from latch bar 130. The dog 139 is provided with an upwardly presented post 144 which is adapted to bear upwardly against a leaf spring 135, and this causes the tip of the detecting finger 134 to be depressed to clear the path of the sheet during the early portion of its forward movement when the dog 139 is sliding along the higher smooth portion 130^a of the upper edge of the latch bar 130. During this movement, the advance edge of sheet S passes over the depressed tip end of finger 135 and holds said finger depressed after the sliding contact of dog 139 on the smooth upper edge 130^a has come to an end. After the post 144 has thus released the finger 134, the advancing sheet is the only instrumentality which holds the finger in depressed position. Referring more especially to Figure 20, it will be noticed that after the latch dog 139 has moved out of engagement with the controlling surface 130^a, it is suspended over the latch bar 130 by means of the interengaging shoulders 142 and 143 which are provided on latch dog 139 and finger 134, respectively. Said latch dog is thus suspended until such time as the detecting finger 134 is released from the sheet and swings upwardly as shown in Figure 21. As the shoulder 143 is withdrawn from its support of the shoulder 142, the latch dog 139 drops into engagement with the latch bar 130. This action interrupts the forward movement of the rack bar 107 and thus terminates the rearward movement of the rack bar 83. As a result the gripper operating cam 80 is automatically located for releasing the sheet when it reaches a predetermined arrangement with respect to the line upon which it is to be folded. The operation of the machine will now be readily understood and briefly related is as follows.

Operation.

It has been observed that in the present embodiment of my invention, the gear 110 has the same number of teeth as the pinion 96, whereas the pinion 108 has one half the number of teeth that the spur gear 97 is provided with. It will also be understood that the spur gear 97 may be in clutching engagement with the spur gear 96 as shown in Figure 14 or it may be removed from engagement with the gear 96 and in mesh with the pinion 108. In the former case, when the cam roller 70 upon the rearwardly moving gripper carriage comes into contact with the cam 80, said cam will be carried along thereby and will impart a similar movement to the rack 83. This in turn imparts a rotary movement to pinion 85, shaft 86, and gear 97 which transmits its motion directly to gear 96. In this way, a forward movement is imparted to rack bar 107 which is equal in extent to that of cam 80. At the same time, the spur gear 110 is rotated by the spur gear 96 to impart an opposite rota-

tion to the shaft 109 and thus serves to impart a forward movement to the rack bar 114 which corresponds in direction and extent to the forward movement of the rack bar 107. As the latch 119 is moved forwardly according to Figures 1 and 23, it is brought into position to be connected up with the gripper mechanism which follows that by which it has been displaced. The several parts are thus returned to their proper initial position determined by their location at the instant the latch 119 is released by the arm 126 coming into engagement with the folding bar 128. It is to be observed that each gripper carriage during its movement over the lower run of its travel and as it approaches the line of fold, is operating the resetting device to return the mechanism to its initial position referred to above. Such initial position is established as the head of the sheet passes the line of fold at which time the tip of the sheet detecting finger 134 starts from the line of fold. At the same time, the cam 80 which is movable along the guide rails or tracks 33 at the opposite end of the gripper carriage, is engaged by the cam roller 70 on that end of the gripper carriage. It will be seen therefore that as the cam 80 is being moved by the cam roller 70 in one direction from the line of fold, the detecting finger is moving under the sheet in the opposite direction from the line of fold. Furthermore, just as soon as the tip of detecting finger 134 emerges from the tail of said sheet it is permitted to move upwardly and thereby releases the dog 139 which drops into engagement with the latch bar 130. This action positively locks the mechanism and stops the cam 80 in position, causing it to operate the gripper mechanism for releasing the sheet which is thus positioned in the desired arrangement with respect to the line of fold. In this instance, the head and tail ends of the sheet will be equally distant from the line of fold. In the latter case the spur gear 97 will impart to gear 108 a motion twice as great as its own which will be transmitted thru gears 110 and 96 to the rack bar 107, thereby giving the latter twice as great a displacement as that of cam 80. In consequence the sheet will be released at that instant when only one-third of its length has been carried beyond the folding line and two-thirds remain on the other side.

Claims:

1. In a machine for folding sheets, the combination with sheet folding means operating at regular recurring intervals, of automatic means controlled by the length of a sheet for locating said sheet with respect to said sheet folding means.

2. In a sheet folding machine, periodically operated sheet-folding means, and automatically operated means for locating suc-

cessive sheets of different sizes with respect to said sheet folding means with one edge of each sheet in a predetermined position on one side of the folding line of said sheet folding means and with the opposite edge of said sheet in a predetermined position on the other side of said folding line.

3. In a machine of the character described, the combination of sheet folding means operating at regularly recurring intervals, travelling sheet gripper means for conveying a sheet into position to be folded by said sheet folding means, means for detecting the presence of one edge of a sheet in a predetermined position on one side of the folding line of said sheet folding means, and means under the control of said detecting means for operating said sheet gripper means to release said sheet with its opposite edge in a predetermined position on the other side of said folding line.

4. In a sheet folding machine, sheet folding means operating at regularly recurring intervals, means for conveying sheets into position to be folded by said sheet folding means, means controlled by the lengths of said sheets for detecting the presence of corresponding edges of successive sheets of different lengths in predetermined positions with respect to the folding line of said sheet folding means, and means under the control of said detecting means for operating said sheet conveying means to release successive sheets with their corresponding ends disposed at distances from the folding line corresponding to the respective lengths of said sheets.

5. In a sheet folding machine, sheet folding means operating along a fixed folding line, travelling sheet gripper means for conveying successive sheets of different lengths into position to be folded by said sheet folding means, means for detecting the presence of corresponding edges of successive sheets in predetermined positions on one side of said fixed folding line, said positions corresponding respectively to the lengths of said sheets, and means under the control of said detecting means for operating said sheet gripper means to release said sheets.

6. The combination with periodically operated sheet folding means, of automatic means for locating the lines of folding on successive sheets of different sizes operated upon by said sheet folding means.

7. The combination with sheet folding means, of travelling sheet feeding grippers for feeding successive sheets of different sizes into position to be folded by said sheet folding means, and means controlled by the sizes of successive sheets for automatically releasing them from said sheet feeding grippers and permitting them to come to rest in sheet folding position.

8. The combination with periodically operated sheet folding means, of means for va-

riably locating successive sheets of different sizes with respect to a fixed line along which said folding means is adapted to operate.

9. The combination with sheet folding means adapted to fold sheets along a predetermined line in the path of feed of sheets to be folded, of sheet conveying means adapted to convey a sheet across said line of folding and means adapting said conveying means to deposit sheets in different positions with respect to said folding line.

10. In a sheet folding machine, a travelling gripper, sheet folding means, and means for operating said gripper in variable positions with respect to said sheet folding means for predetermining the extent of the different portions of said sheet to be arranged on opposite sides of the line along which said sheet is to be folded.

11. The combination with sheet folding means, of means for variably locating a sheet with respect to the line along which said folding means is adapted to operate, said locating means being controlled by a sheet located thereby.

12. The combination with sheet folding means adapted to fold sheets along a predetermined line in the path of feed of sheets to be folded, of sheet conveying means adapted to convey a sheet across said line of folding, and means adapting said conveying means to deposit sheets in different positions with respect to said folding line, said sheet conveying means being under the control of a sheet conveyed thereby.

13. In a sheet folding machine, a travelling gripper, sheet folding means, and means for operating said gripper in variable positions with respect to said sheet folding means for predetermining the extent of the different portions of said sheet to be arranged on opposite sides of the line along which said sheet is to be folded, said gripper operating means being under the control of a sheet conveyed by said gripper.

14. In a machine of the character described, sheet folding means, a travelling gripper mechanism, and means for operating said gripper mechanism in variable positions depending upon the size of the sheet to be located with respect to said sheet folding means.

15. In a machine of the character described, sheet folding means, a travelling gripper mechanism, and means for operating said gripper mechanism in variable positions depending upon the size of the sheet to be located with respect to said sheet folding means, the said operating means comprising a cam movable under the control of a sheet into position to operate said sheet gripping mechanism.

16. In a machine of the character described, means for folding a sheet along a predetermined line, sheet feeding gripper

mechanism for presenting a sheet in suitable position to be folded along said folding line, and a sheet controlled device adapted to operate said gripper mechanism to locate predetermined portions of said sheet on opposite sides of said folding line.

17. In a machine of the character described, means for folding a sheet on a predetermined line, sheet gripper mechanism for conveying a sheet into position to be folded thereby, a cam movable into and out of predetermined positions to operate said gripper mechanism, said cam being adapted to be moved into operative position by means of said gripper mechanism, and means for locking said cam in operative position, said locking means being normally held inoperative by a sheet until it reaches a predetermined position.

18. In a machine of the character described, sheet folding means, a plurality of travelling gripper mechanisms for moving successive sheets into position to be folded by said sheet folding means, a cam disposed in the path of said gripper mechanism and movable thereby into position to operate said gripping mechanisms, sheet controlled means for locking said cam in operative position with respect to one sheet gripper mechanism and means disposed in the path of another gripper mechanism for returning said cam to a position to be engaged by a succeeding gripper mechanism.

19. The combination with periodically operated sheet folding means, of means for automatically locating the folding lines on successive sheets of different sizes to be operated upon by said sheet folding means, said locating means being adapted to vary the proportional parts of said sheets to be arranged on opposite sides of the folding line.

20. The combination with sheet folding means, of sheet controlled means for locating successive sheets of different sizes to arrange predetermined portions of each sheet on opposite sides of the line of fold imparted by said folding means, and means for changing the relative proportions between the portions of each sheet on opposite sides of the folding line.

21. The combination with sheet folding means, of a plurality of sheet gripper mechanisms travelling in a suitable path to present successive sheets to said folding means, means for operating the grippers of successive sheet gripper mechanisms to release the successive sheets with predetermined portions thereof on opposite sides of the folding line imparted by said folding means, said sheet gripper operating means being controlled by the successive sheets which are conveyed by said sheet gripper mechanisms.

22. In a machine of the character described, sheet folding means, a travelling sheet gripper mechanism, a gripper operat-

ing cam movable into and out of position to operate said gripper mechanism for releasing a sheet, and sheet controlled means for determining the operating position of 5 said cam.

23. In a machine of the character described, sheet folding means, a travelling sheet gripper mechanism, a cam in the path of said sheet gripper mechanism, and movable thereby, said cam being adapted when locked against movement to operate said gripper mechanism, a sheet detecting finger and means under the control of said sheet detecting finger for locking said cam against 10 movement when a sheet reaches a position to be folded by said sheet folding means.

24. In a machine of the character described, sheet folding means, a sheet gripper mechanism movable into and out of position 20 to present a sheet to said sheet folding means, a gripper operating cam mounted in the path of said sheet gripper mechanism, and adapted to be moved thereby, a sheet detecting finger mounted in the path of a sheet 25 conveyed by said sheet gripper mechanism, and means under the control of said sheet detecting finger for locating said cam in position to operate said gripper mechanism.

25. In a machine of the character described, sheet folding means, a travelling sheet gripper mechanism, a cam moved by said gripper mechanism, said cam being adapted when locked against movement to operate said gripper mechanism, sheet controlled means for locking said cam against 30 movement, and means for returning said cam to an initial position from which it was displaced by the movement of said gripper mechanism.

40 26. In a machine of the character described, sheet folding means, sheet gripper mechanism movable into and out of position to present a sheet to said sheet folding means, a cam adjustably mounted in the 45 path of said sheet gripper mechanism, a rack bar connected to said cam, a shaft geared to said rack bar, a sheet detecting finger mounted in the path of a sheet conveyed by said sheet gripper mechanism, and means 50 under the control of said sheet detecting finger for locating said cam to release a sheet in position to be folded by said sheet folding means.

55 27. In a machine of the character described, sheet folding means, a gripper carriage movable in a predetermined path, a transverse series of sheet gripper elements mounted on said carriage, tracks or guides for the opposite ends of said carriage, a cam 60 slidably mounted in the path of one end of said carriage, said cam being adapted to be displaced by said gripper carriage to a position to operate the latter when the sheet has been conveyed into a predetermined position with respect to said sheet folding 65

means, means mounted in the path of the other end of said carriage and operably connected to said cam for returning said cam to initial position from a previous operation, and sheet controlled means for predetermining the position of said cam for releasing said sheet. 70

28. In a machine of the character described, sheet folding means, a gripper carriage movable in a predetermined path, a transverse series of sheet gripping elements 75 mounted on said carriage, tracks or guides for the opposite ends of said carriage, a cam slidably mounted in the path of one end of said carriage, said cam being adapted to be displaced by said gripper mechanism to a position to operate the latter when the sheet has been conveyed into a predetermined position with respect to said sheet folding means, sheet controlled means for predetermining the position of said cam for releasing said sheet, and means for operatively connecting said cam and sheet controlled means, including change gears for varying the operation of said sheet controlled means 80 with respect to said cam. 85

29. In a machine of the character described, sheet folding means, a gripper carriage movable in a predetermined path, a transverse series of sheet gripping elements 90 mounted on said carriage, tracks or guides for the opposite ends of said carriage, a cam slidably mounted in the path of one end of said carriage, said cam being adapted to be displaced by said gripper mechanism to a position to operate the latter when the sheet has been conveyed into a predetermined position with respect to said sheet folding means, a resetting device slidably mounted in the path of the other end of said carriage, means for operably connecting said cam and resetting device, and sheet controlled means for predetermining the position of said cam for releasing said sheet, said resetting device being provided with means for 100 releasably engaging the sheet gripper carriage for returning the cam to initial position. 105

30. In a machine of the character described, sheet folding means, a gripper carriage movable in a predetermined path, a transverse series of sheet gripping elements mounted on said carriage, tracks or guides for the opposite ends of said carriage, a cam 110 slidably mounted in the path of one end of said carriage, said cam being adapted to be displaced by said gripper mechanism to a position to operate the latter when the sheet has been conveyed into a predetermined position with respect to said sheet folding means, and sheet controlled means for predetermining the position of said cam for releasing said sheet, said sheet controlled means comprising a rack bar movably connected to said cam, a latch bar extending in 115 120 125 130

juxtaposition thereto, a dog pivotally connected to said rack bar, and adapted to engage said latch bar, and a sheet controlled finger for controlling the operation of said dog.

31. In a machine of the character described, side frames, a sheet gripper carriage having opposite ends slidably mounted in said side frames, racks reciprocably mounted in said side frames, a cam connected to one of said racks and disposed in the path of one end of said carriage, a latch connected to the other one of said racks for releasably connecting said rack to the other 15 end of said carriage, transverse shafts geared together and respectively to said racks, an intermediate rack connected to said cam thru one of said transverse shafts, means for locking said intermediate rack to 20 a rigid portion of the machine, and a sheet detecting finger for controlling the operation of said locking means.

32. In a machine of the character described, side frames, a sheet gripper carriage having opposite ends slidably mounted in said side frames, racks reciprocably mounted in said side frames, a cam connected to one of said racks and disposed in the path of gripper bearing means on one end of 25 said carriage, a latch connected to the other of said racks for releasably connecting said rack to the other end of said carriage, transverse shafts geared respectively to said racks, an intermediate rack having means 30 for locking it to a rigid portion of the machine, a sheet detecting finger for controlling the operation of said locking means, gears of different sizes keyed to one of said shafts, a gear loosely journalled on the other of said shafts and having meshing engagement with said intermediate rack and one 35 of the last mentioned gears, and a third gear having splined connection with the other shaft and provided with means adapting it to be clutched to said loosely journalled gear or to be placed in mesh with the other of 40 said gears keyed to the other shaft.

33. In a machine of the character described, a receiving conveyer provided with 45 means for gripping the folded edge of a sheet, a folder blade suitably mounted to cooperate with said gripping means for folding a sheet while at the same time presenting the folded edge of said sheet to said gripping means, and means for variably locating successive sheets of different sizes 50 with respect to said folding means.

34. In a machine of the character described, a receiving conveyer provided with 55 means for gripping the folded edge of a sheet, a folder blade suitably mounted to cooperate with said gripping means for folding a sheet while at the same time presenting the folded edge of said sheet to said gripping means, and means for locating suc- 60

cessive sheets of different sizes with respect to their sizes to arrange predetermined portions of sail sheets on opposite sides of the folding blade.

35. In a machine of the character de- 70 scribed, a folding blade, means for conveying successive sheets of different sizes into position with predetermined portions of each sheet on opposite sides of said folding blade, and sheet gripping means movable into position to cooperate with said folding blade for folding said sheet and movable out of such position with the folded edge of the sheet gripped thereby.

36. In a machine of the character de- 80 scribed, sheet gripping means movable over a predetermined path, sheet controlled means for operating said sheet gripping means to release successive sheets of different sizes with predetermined portions of the sheets 85 located with respect to the folding line, other sheet gripping means movable over a predetermined path, and a folding blade co-operating with said sheet gripping means for folding successive sheets. 90

37. In a machine of the character de- 95 scribed, sheet gripping means movable over a predetermined path, sheet controlled means for operating said sheet gripping means to release successive sheets of different sizes located with respect to a folding line, other sheet gripping means movable over a pre- 100 determined path; and a folding blade mounted on a fixed axis and cooperating with said sheet gripping means in succession for folding sheets.

38. In a machine of the character de- 105 scribed, side frames, a sheet gripper carriage having opposite ends slidably mounted in said side frames, racks reciprocably mounted in said side frames, a cam connected to one of said racks and disposed in the path of one end of said carriage, a latch connected to the other of said racks for re- 110 leasably engaging the other end of said carriage, transverse shafts geared respectively to said racks, an intermediate rack having geared connections with said shafts, means for locking said intermediate rack to a rigid portion of the machine, a sheet detecting 115 finger for controlling the operation of said locking means, gears of different sizes keyed to one of said shafts, a gear loosely journalled on the other of said shafts and having meshing engagement with said intermediate rack and one of the different sized 120 gears, a fourth gear having splined connection with the other shaft and provided with means adapting it in one position to be connected to said loosely journalled gear and in another position to be placed in mesh with one of said different sized gears, and means for adjusting the position of said splined gear. 125 130

39. In a machine of the character described, sheet folding means, travelling gripper carriages provided with releasable grippers, tracks or guides for the opposite ends of said carriage, and means movable by the movements of said carriages into and out of position to operate said grippers.
40. In a machine of the character described, sheet folding means, a gripper carriage movable in a predetermined path, a transverse series of sheet gripper elements mounted on said carriage, a cam mounted in the path of one end of said carriage, said cam being adapted to be displaced thereby to a position in which it is adapted to operate the sheet gripper elements, and sheet controlled means for predetermining the position of said cam for releasing said sheet.
41. In a machine of the character described, sheet folding means, a plurality of gripper carriages movable in a predetermined path, releasable grippers carried by said carriages, a cam for operating said grippers, said cam being movably mounted in the path of said carriages, sheet controlled means for interrupting the displacement of said cam and for adapting it to operate said grippers, and means mounted in the path of another of said carriages, for returning said cam to initial position.
42. In a machine of the character described, sheet folding means, a gripper carriage movable in a predetermined path, sheet gripping means mounted on said carriage, a cam slidably mounted in the path of said carriage, said cam being adapted to be displaced by said carriage, sheet controlled means for interrupting the movement of said cam, said cam being adapted to release said sheet gripping means, and means disposed in the path of another gripper carriage and operably connected to said cam for returning said cam to initial position.
43. In a machine of the character described, sheet folding means, gripper carriages movable in a predetermined path, sheet grippers mounted on said carriages, a cam slidably mounted in the path of said carriages and adapted to be displaced thereby to a position in which it is adapted to operate the grippers, a resetting device slidably mounted within the path of said carriages, means for operably connecting said cam and resetting device, and sheet controlled means for predetermining the position of said cam for releasing said sheet, each of said carriages being adapted to operate said resetting device for returning said cam to initial position and immediately thereafter to move said cam to sheet releasing position under the control of said sheet controlled means.
44. In a machine of the character described, sheet folding means, a gripper carriage movable in a predetermined path, a transverse series of sheet gripping elements mounted on said carriage, tracks or guides for the opposite ends of said carriage, a cam slidably mounted in the path of one end of said carriage, said cam being adapted to be displaced by said gripper carriage to a position to operate the latter, a sheet detecting finger movably mounted in the path of sheets conveyed by said carriage, and means for operably connecting said cam and detecting finger for locating said cam for releasing sheets from said sheet gripping elements.
45. In a machine of the character described, sheet folding means, a gripper carriage movable in a predetermined path, a gripper mounted on said carriage, a cam for operating said gripper, said cam being adapted to be displaced by said carriage to a position to operate the gripper when the sheet has been conveyed into a predetermined position with respect to said sheet folding means, a locking device provided with sheet detecting means arranged in the path of sheets conveyed by said carriage, and means including change gears for connecting said cam and locking device.
46. In a machine of the character described, sheet folding means, gripper mechanism movable in a predetermined path, gripper operating means movable into operating position for each sheet folding operation, and sheet controlled means for predetermining the position of said gripper operating means for releasing said sheet, said sheet controlled means comprising a rack bar movable with said gripper operating means, a latch bar extending in juxtaposition thereto, a latch pivotally connected to said rack bar and adapted to engage said latch bar, and a sheet controlled finger for controlling the operation of said latch depending upon the sizes of successive sheets to be folded.
47. In a machine of the character described, sheet folding means, a gripper movable in a predetermined path, means for operating said gripper at one stage of its movement to grip a sheet, and sheet controlled means for opening said gripper at another stage of its movement to release said sheet in position to be folded, said sheet controlled means including a movable latch, a latch bar along which said latch moves, and a sheet controlled finger for controlling the operation of said latch.
48. In a machine of the character described, sheet folding means, a carriage movable in a predetermined path, gripper mechanism mounted on said carriage, a cam mounted in the path of said carriage and adapted to be displaced thereby into position in which it is adapted to operate said gripper mechanism, and sheet controlled means for predetermining the position of

5 said cam for releasing said sheet, said sheet controlled means comprising a rack bar movable with said cam, a latch bar extending in juxtaposition thereto, a latch pivotally connected to said rack bar and adapted to engage said latch bar, and a sheet controlled finger for controlling the operation of said latch.

10 49. In a machine of the character described, side frames, sheet gripper mechanism movably mounted in said side frames, a rack reciprocably mounted in one of said side frames, gripper operating means connected to said rack, a transverse shaft geared to said rack, a second rack geared to said shaft, means for locking said second rack to a rigid portion of the machine, and a sheet detecting finger for controlling the operation of said locking means.

15 50. In a machine of the character described, sheet folding means, side frames, a sheet gripper carriage having opposite ends movably supported in said side frames, racks slidably mounted in said side frames respectively, a cam connected to one of said racks and disposed in the path of one end of said carriage, a latch connected to the other one of said racks for releasably connecting said rack to the other end of said carriage, trans-

20 verse shafts geared respectively to said racks, geared connections connecting said shafts, and a sheet controlled finger for interrupting the movements of said racks in variable positions depending upon the sizes

25 of the sheets fed to said sheet folding means.

51. In a machine of the character described, side frames, sheet gripper mechanism slidably mounted in said side frames, a rack reciprocably mounted in one of said side frames, means operated by said rack for opening the gripper mechanism, an intermediate rack, means for locking said intermediate rack to a rigid portion of the machine, a sheet detecting finger for controlling the operation of said locking means, and means including change gears for connecting said racks in different displacement ratios.

52. In a machine of the character described, side frames, a sheet gripper carriage having opposite ends slidably mounted in said side frames, racks reciprocably mounted in said side frames, a cam connected to one of said racks and disposed in the path of one end of said carriage, a latch connected to the other one of said racks for releasably connecting said rack to the other end of said carriage, transverse shafts geared respectively to said racks, and to each other, an intermediate rack having geared connections with said shafts, means for locking said intermediate rack to a rigid portion of the machine, and a sheet detecting finger for controlling the operation of said locking means.

53. In a machine of the character described, sheet detecting means adapted to become operative when a sheet reaches a predetermined position with respect to its size, means for feeding successive sheets of different sizes into said position, and means controlled by the sizes of successive sheets for releasing said sheet from said feeding means as they successively reach said position.

75 54. Mechanism for positioning successive sheets of different sizes with respect to a predetermined line of fold and with the same proportional parts of each sheet arranged on opposite sides of said line, said mechanism comprising releasable gripper mechanism for conveying successive sheets into position with respect to said line, and means controlled by the sizes of successive sheets for releasing said gripper mechanism.

80 55. In a machine of the character described, sheet folding means operating at regularly recurring periods and adapted to operate upon the same relative portions of successive sheets of different sizes, and means controlled by the sizes of successive sheets for similarly locating successive sheets with respect to said sheet folding means.

85 56. In a machine of the character described, periodically operated sheet folding means, means automatically controlled by the lengths of successive sheets of different lengths for determining the proportional parts of said sheets to be arranged on opposite sides of the folding line of said sheet folding means, and means for varying the proportions of each sheet to be arranged on opposite sides of the folding line.

90 57. The combination with sheet folding means, of travelling sheet feeding grippers for moving successive sheets of different sizes into position with respect to a fixed folding line, and automatic means for operating said grippers at predetermined times depending upon the sizes of successive sheets to release said sheets in position to be folded along said fixed folding line.

105 58. The combination with sheet folding means, of sheet conveying means, and automatic means for operating said sheet conveying means to deposit successive sheets of different sizes in position to be folded by said sheet folding means.

115 59. In a sheet folding machine, a travelling gripper, sheet folding means operating upon a predetermined line of fold, and automatic means for operating said gripper in variable positions with respect to said folding line for locating the lines of folding on successive sheets of different sizes.

120 60. The combination with sheet folding means, of a plurality of sheet gripper mechanisms movable past said sheet folding means, and automatic means for variably
